LIGHT REFLECTING MEANS

Charles Daniel Ryder, Covington, Ky., assignor to
 The National Colortype Company, Bellevue,
 Ky., a corporation of Kentucky

Application March 12, 1935, Serial No. 10,682

23 Claims. (Cl. 88—82)

The present invention relates to light reflecting means of the type employed in connection with various signs adapted to be rendered visible by reflected light from an external source. Light reflecting devices of this class may be employed in connection with advertising signs although they are particularly serviceable as warning signals and are especially adapted for use on highways where they are rendered visible by the light reflected from the headlights of motor vehicles approaching the sign at night. The construction of the sign may be varied to suit different conditions and any desired number of the new and novel light reflecting units may be employed for use with different signs.

One object of the invention is to provide in a sign of this class, a compact self-contained light reflecting unit which may be readily applied to a supporting member therefor merely by inserting it within an aperture thereof without the use of tools or other devices.

A further object of the invention is to provide in conjunction with the light reflecting units, one or more securing parts thereon, which when the units are moved to final position on the supporting means therefor will engage and interlock with the latter in such a manner as to prevent withdrawal of the units from the supporting means.

30 A further object of the invention is to provide an improved sign, including one or more plate or display members having light reflecting units inserted within apertures thereof and held against withdrawal therefrom by parts located on and moving with the units when applying them to said members whereby to economize in the cost of assembling the light reflecting units upon the sign.

40 A further object of the invention is to provide a light reflecting unit including a lens and a holder for the unit having a resilient securing part or parts thereon, insertable with the unit through openings in supporting members therefor of different thicknesses with which said parts will cooperate to secure the units against retraction or withdrawal through said openings.

45 A further object of the invention is to provide an improved sign embodying display means which may include the front wall of a casing or housing, having a series of apertures arranged in any preferred manner and having inserted therein improved light reflecting units with securing parts thereon adapted to cooperate with said wall to prevent withdrawal of the units therefrom.

55 A further object of the invention is to provide

a light reflecting element and securing means therefor combined therewith to form a unitary device of simple construction which can be manufactured at a relatively low cost and assembled upon a supporting member for interlocking engagement therewith when moved to a predetermined position thereon.

To these and other ends the invention resides in certain improvements and combinations of parts, all as will be hereinafter more fully described, the novel features being pointed out in the claims at the end of the specification.

In the drawing:

Fig. 1 is a front elevation of a light reflecting sign or display member embodying the invention;

Fig. 2 is a sectional elevation on the line 2—2 of Fig. 1 drawn to an enlarged scale and illustrating the application of one of the light reflecting units to the supporting plate therefor;

Fig. 3 is a similar view in which the light reflecting unit is shown in a different position from that shown in Fig. 2 to further illustrate the means by which the unit is secured upon the support;

Fig. 4 is a view similar to Fig. 3, except that the cup-shaped element telescoped upon the light reflecting unit is shown in section;

Fig. 5 is a sectional elevation on line 5—5 of Fig. 3;

Fig. 6 is a perspective view of the cup-shaped element shown in section in Fig. 4;

Fig. 7 is a front elevation of said element, and

Fig. 8 is a sectional view illustrating a modified form of the invention.

The same reference numerals throughout the several views indicate the same parts.

In the present embodiment of the invention the light reflecting unit has thereon securing means therefor which together with the unit can be applied to the display or front wall of a housing merely by pushing the unit rearwardly to a predetermined position within an aperture of said wall, in which position the securing means will engage a portion of the wall, preferably the rear portion thereof surrounding the aperture and in such a manner as to lock or secure the unit against retraction or withdrawal from the aperture, this being true of plates or walls of different thicknesses, within certain limits. It will therefore be seen that light reflecting units constructed in this manner can be conveniently and rapidly assembled in position upon a sign plate to complete the sign, without the use of tools or other devices, whereby the cost of constructing the sign is considerably reduced.

The sign shown in Fig. 1 of the drawing by way of illustration may comprise any suitable display plate or background provided with the desired number of light reflecting units or elements arranged in any preferred manner, and corresponding to characters of any preferred design.

The element 10 may comprise a housing or the front wall or display plate of a complete sign, or 10 one section of a sign formed of a plurality of such elements. Where the element is constructed in the form of a housing it will serve to enclose the portions of the light reflecting units projecting rearwardly of the front or display plate through 15 the openings 11 therein. The light reflecting units are designated generally by the reference character 12 and include a suitable lens 13 extending within a casing 14, the lens being provided with suitable reflecting means within the 20 casing not shown. The lens casing is provided with a flange or shoulder 15 at the front end thereof which is adapted to engage the front side of the plate 10 to limit rearward movement of the light reflecting unit when positioning it within 25 the aperture of the plate.

The casing 14 of the light reflecting unit as provided with a threaded extension 16 which is projected through an opening in the end wall 17 of a cup-shaped holding member 18 sleeved on 30 the lens casing 14, as best shown in Fig. 4. The front end of the cup-shaped member extends within the aperture 11 of the plate 10 and engages the flange or shoulder 15 of the casing against which it is urged by the clamping action of the 35 nut 19 on the threaded extension 16.

The means for securing the light reflecting unit on the supporting plate 10, in one disclosure, is carried by and preferably formed integral with the holder 18 for the light reflecting unit, said 40 means comprising the outwardly extending yieldable tongue-like parts 20 preferably formed by slotting the holder longitudinally and transversely thereof and bending said parts to cause them to project outwardly from the sides of the holder 45 as best shown in Figs. 5, 6, and 7. It will be noted that the securing parts 20 are of tapered construction and that they are substantially of the same curvature as that of the cup-shaped member from which the parts are formed. The front edge of 50 the securing member is preferably serrated to provide it with a series of teeth 21, the extremities of which lie in a plane inclined to the plane of the supporting plate 10, as indicated in Figs. 3 and 4. The rear edge 22 of the securing member 55 is also in a plane inclined to the plane of the supporting plate 10 so that it constitutes in effect a cam, which when the light reflecting unit is inserted within the aperture of the supporting plate will be engaged by that portion of the plate 60 surrounding the aperture which will cause the securing member to be cammed inwardly toward the lens casing. When, however, the light reflecting unit has been moved to final position with the flange 15 of the lens casing in engagement with the front side of the supporting plate 65 the deflected resilient securing member will spring outwardly, at which time one of the teeth of each of said members will engage and interlock with the portion of the supporting plate at or adjacent the rear side thereof, whereby the light reflecting 70 unit will be securely retained on the plate and held against withdrawal therefrom. Furthermore, the pressure exerted by the resilient securing parts 20 on the plate 10 is sufficient to 75 firmly clamp the flange 15 of the light reflecting

unit in engagement with the front face of the supporting plate whereby the unit is held properly centered within the aperture of the plate.

By reason of the inclination of the front portion of the securing member 20 to the rear face of the supporting plate 10, said securing member will accommodate itself to plates of different thicknesses, within certain limits which is advantageous since it avoids having to make up different securing devices for different signs constructed of plates of varying thicknesses. In other words the light reflecting units are made interchangeable for use with signs having display plates of different thicknesses.

It will be understood that the teeth 21 of the securing member 20 may be omitted, in which case the unbroken front edge of said member will engage the rear portion of the supporting plate, and since said edge extends at an angle to the face of the plate a wedging action will be afforded 20 between said parts, due to the tendency of the securing member to spring outwardly to normal position, this being true also where the securing member is serrated as shown in Fig. 6. The wedging action of the oppositely disposed securing 25 members will operate to urge the flange 15 of the lens casing in engagement with the front face of the supporting plate whereby the light reflecting unit will be firmly held in position on said plate.

In addition to the securing members 20 of the light reflecting unit, the holder 18 is provided with outwardly struck yieldable tongues 23, the front edge portions of which may either be parallel to the rear face of the supporting plate, as 30 shown, or inclined relative thereto, as are the front edges of the securing parts 20. The tongue-like members 23 are provided for cooperation with a supporting plate which may be slightly thicker than one of the maximum thickness 40 which the securing members 20 are designed to accommodate. The securing parts 23 like the parts 20 will prevent withdrawal of the light reflecting units outwardly through the apertures 11 of a supporting plate of a predetermined thickness. Furthermore the securing parts 23 will be 45 deflected inwardly by said supporting plate and will pass through the aperture therein and spring outwardly to the position shown in Figs. 3 and 4 to prevent subsequent withdrawal of the 50 light reflecting unit from said plate. The light reflecting units may, however, be released for removal from the supporting plate merely by unscrewing the nut 19 and withdrawing the cup-shaped holder 18 from the unit.

In the modification shown in Fig. 8 the principle of operation of the securing parts for the light reflecting units is the same as that described above in connection with the disclosures of Figs. 1 to 7, inclusive. However, in this arrangement the 60 cup-shaped holder is omitted, and likewise the screw extension of the light reflecting unit, said unit being otherwise the same as that shown in Fig. 4. The light reflecting unit of Fig. 8 comprises the lens 13a and the casing 14a therefor, 65 having a flange 15a for limiting the movement of the unit rearwardly within the aperture 11a of the supporting plate 10a.

The securing means for the light reflecting unit of said modification preferably comprises a continuous ring or band 24, encircling the front portion of the lens casing in abutting relation with respect to the flange 15a thereof and may be detachably or permanently secured on the casing as preferred, by any suitable means, as, for ex- 75

ample, by one or more pins 25 anchored in the wall of the casing 14a in engagement with the rear edge of said band which is prevented from rotating on the lens casing by said pins. The band is formed of resilient or spring-like material and is provided with a pair of oppositely disposed outwardly struck securing members 26, similar to the securing members 20 of Fig. 6, except that the teeth of the latter have been omitted.

The securing members 26 are curved to conform substantially to the curvature of the band from which they are formed and normally project outwardly therefrom. The front and rear edges 27 and 28 of said securing member are convergently arranged and each is inclined relative to the plane of the supporting plate 10a. The rear edge portion 28 of said securing member forms in effect a cam, which when inserting the light reflecting unit within the aperture 11a, will be engaged by the portion of the plate surrounding the aperture whereby the securing member will be cammed inwardly toward the lens casing. As soon however as the light reflecting unit is moved to final position, with the flange 15a in engagement with the front face of the supporting plate, the securing member will spring outwardly to operating position, in which a portion of its front edge will become wedged into engagement with the rear portion of the supporting plate to clamp and hold the light reflecting unit in position upon said plate. The band 24 is also provided with outwardly struck resilient tongue-like portions 29 corresponding to the tongue-like members 23 of the cup-shaped member 18 and provided for the same purpose.

In applying either of the light reflecting units described herein to the supporting plate, all that is necessary is to insert them within the apertures provided therefor and at the same time move them rearwardly to final position, an operation which can be quickly performed, whereby the time required in assembling and securing the several light reflecting units upon the display plate of the sign is reduced to a minimum. However, in thus applying the light reflecting units to the supporting plate they can, if desired, be given a rotating movement coincident with the operation of pushing them into position within the openings of said plate.

As previously stated, one advantage of light reflecting units constructed as shown and described herein is the saving in time and cost of labor afforded by reason of the fact that no parts have to be applied to the units to secure them upon the display plate after they have been positioned in the openings thereof as had been necessary heretofore in signs of this type.

A very considerable saving in the cost of producing the signs is also afforded by reason of the novel method of constructing and applying the individual light reflecting units thereto. This is true since the light reflecting units are applied to a single supporting plate, whereas in previous designs it has generally been customary to mount the units on at least two or three supporting plates. The omission of such additional plates from the present design and the parts associated therewith for securing the light reflecting units thereon, makes it possible to greatly economize, both in the cost of materials and labor, as will be apparent for the reasons stated.

I claim:

1. In light reflecting means, a supporting member having an aperture therein, a light reflecting

device, said device having a resilient securing part thereon provided with a cam-like portion, said device and resilient securing part being movable as a unit within said aperture to a predetermined position during which movement said cam-like portion will be engaged by the supporting member and depressed thereby within said opening, said resilient part upon movement of the light reflecting device to said predetermined position springing outwardly and having a wedging action on the supporting member, and means on said light reflecting device for engaging the supporting member to check the movement of the light reflecting device at said predetermined position, said means being urged in engagement with the supporting member by the wedging action of said resilient part.

2. In light reflecting means, a supporting plate having an aperture therein, a light reflecting device including a lens, and a resilient securing part on said device, said part having an edge portion extending transversely of the axis of the lens and inclined relative to the supporting plate to accommodate the device to plates of different thicknesses, the light reflecting device and securing part being insertable within the aperture of the plate and the resilient securing part being moved through contact with the plate inwardly toward the axis of the lens during movement of the light reflecting device to a predetermined position within the aperture, at which position said resilient part will spring outwardly to move said edge portion in contact with the rear portion of the supporting plate whereby to clamp the light reflecting device on the plate.

3. In light reflecting means, a supporting plate having an aperture therein, a light reflecting device including a lens, and a resilient securing part on said device, said part having an edge portion extending transversely of the axis of the lens and inclined relative to the supporting plate to accommodate the device to plates of different thicknesses, the light reflecting device and securing part being insertable within the aperture of the plate and the resilient securing part being moved through engagement with the wall of the plate inwardly toward the axis of the lens during movement of the light reflecting device to a predetermined position within the aperture at which position said resilient part will spring outwardly to wedge said edge portion in contact with the rear portion of the plate, and means on the light reflecting device for engaging the front side of the plate to limit movement of the device rearwardly within the aperture, said means being urged in engagement with the plate by the wedging action of said resilient part.

4. In light reflecting means, a supporting plate having an aperture therein, a light reflecting device including a lens, and a resilient securing part on said device, said part having front and rear edge portions each inclined relative to one face of said plate, said device being movable within said aperture to a predetermined position during which movement the rear edge of said securing part will ride on said plate to force said part in the direction of the axis of the lens, said part automatically moving outwardly to position the front edge portion thereof in engagement with the rear portion of the supporting plate when the light reflecting device is moved to said predetermined position.

5. A light reflecting device for insertion within apertures of supporting plates of different thicknesses, said device including a lens and a casing

therefor having resilient securing parts arranged one in advance of another each for cooperation with one of said plates to prevent withdrawal of said device therefrom, the resilient parts of said device being deflected inwardly thereof through engagement with the supporting plate when being moved within the aperture thereof and each having an edge portion inclined relative to the axis of the lens, said parts springing outwardly in a predetermined position of said device and the edge portions thereof being adapted to have a wedging action on the supporting plate whereby to secure the device thereon.

6. In light reflecting means, a display member having an aperture therein, a light reflecting device, and front and rear yieldable parts on said device, said parts being movable with said device as a unit rearwardly through the aperture of said display member and each being deflected inwardly through contact with the portion of the wall of said display member surrounding the aperture when passing through the aperture, said parts each springing outwardly when emerging from the aperture and one having a front edge portion inclined relative to the rear face of the display member and having a wedging action thereon whereby to secure the reflecting device upon the display member.

7. In light reflecting means, a supporting member having an aperture therein, a light reflecting unit including a lens and a casing for the lens, and a device detachably mounted on said casing and having front and rear yieldable parts, said device and yieldable parts being movable with the casing as a unit rearwardly through the aperture of said supporting member, each of said yieldable parts being deflected inwardly through contact with the portion of the wall of the supporting member surrounding the aperture while passing through the latter, said parts each springing outwardly when emerging from the aperture and one having an edge portion inclined relative to and having a wedging action on the rear side of the supporting member.

45 8. In light reflecting means, a supporting member having an aperture therein, a light reflecting device including a lens and a casing for the lens having a resilient securing part thereon insertable with the casing as a unit in said aperture, said part having an edge portion extending transversely of the axis of the lens and engaging the supporting member and having a wedging action thereon in a predetermined position of the casing to hold the latter against retraction through said aperture.

9. In light reflecting means, a supporting member having an aperture therein, a light reflecting device including a lens having a casing therefor provided with a shoulder, and a resilient securing part on the casing movable therewith into said aperture, said resilient part having an edge portion inclined relative to the rear face of the supporting member, said shoulder engaging one side of the supporting member when the casing is moved to a predetermined position within the aperture in which position the inclined edge portion of the resilient securing part will have a wedging action on the supporting member whereby to urge said shoulder in engagement with the supporting member.

10. In light reflecting means, a supporting member having an aperture therein, a light reflecting device including a lens and a casing therefor insertable within said aperture and having a shoulder for engaging the supporting mem-

ber at one side thereof to limit movement of the casing to a predetermined position within the aperture, and oppositely disposed resilient securing members on the casing having edge portions inclined relative to the rear face of the supporting member, said resilient securing members being deflected inwardly by the supporting member when moving the casing to said predetermined position at which position said resilient securing members will automatically move outwardly to cause the inclined edge portions thereof to have a wedging action on the supporting member whereby to hold the casing against retraction through said aperture.

11. In light reflecting means, a supporting plate having an aperture therein, a light reflecting unit including a lens and a casing therefor, and a holding device for the unit sleeved on said casing and provided with outwardly struck resilient parts having front edge portions inclined relative to the supporting plate, said unit and holding device being moved rearwardly through the aperture of the supporting plate and said resilient parts being deflected inwardly by said plate while moving through said aperture, said parts springing outwardly when emerging from the aperture on the rear side of the plate and said inclined edge portions each having a wedging action on the supporting plate whereby to secure the light reflecting unit thereon.

12. In light reflecting means, a supporting plate having an aperture therein, a light reflecting unit including a lens and a casing therefor, a holding device for the unit sleeved on said casing and provided with a rear wall and with outwardly struck resilient parts, said unit and holding device being moved rearwardly through the aperture of the supporting plate and said resilient parts being deflected inwardly by said plate while moving through said aperture, said parts springing outwardly when emerging from the aperture on the rear side of the plate and having a wedging action on the plate whereby to secure the unit and holding device against retraction through said aperture, and a threaded member projecting rearwardly from the lens casing through an opening in the rear wall of the holding device, said threaded member having a nut thereon engaging said wall to clamp the holder upon the lens casing.

13. A light reflecting unit for insertion within an aperture of a supporting plate, said unit including a lens and a casing therefor, and oppositely arranged resilient parts on said casing for holding said unit within the aperture of said supporting plate, said parts having edge portions inclined relative to the plate, the parts being adapted for deflection inwardly by said plate when moved through the aperture thereof to a predetermined position and springing outwardly at said position whereby to permit said edge portions to have a wedging action on the plate for the purpose of holding the unit against retraction through said aperture.

14. A light reflecting unit for insertion within an aperture of a supporting plate, said unit including a lens and a casing therefor, a holding member for the unit sleeved on said casing and having oppositely arranged resilient parts provided with edge portions inclined relative to the plane of the supporting plate, said parts adapted for deflection inwardly by said plate when moving through the aperture thereof and springing outwardly when the unit is moved to a predetermined position and adapted to have a wedging action on the plate to hold the unit against retraction

through said aperture, said holding member having a rear end wall thereon, a threaded extension on the lens casing projecting through said rear wall, and a nut on said extension engaging 5 said wall and operating to clamp the holding member upon the casing.

15. In a light reflecting means, a supporting member having an aperture therein, a light reflecting device, and resilient holding means on 10 said device having a front edge portion inclined relative to the rear face of said supporting member, said device and holding means being insertable within said aperture to a predetermined position, said resilient holding means being 15 placed inwardly by the supporting member during movement within the aperture to said position and automatically moving outwardly when the reflecting device is at said position whereby said front edge portion will have a wedging action 20 on the supporting member to clamp the reflecting device thereon.

16. In light reflecting means, a supporting plate having an aperture therein, a light reflecting device, said device being movable within the aperture to a predetermined position and having a resilient securing part movable therewith and provided with a front edge portion extending interiorly and exteriorly of the aperture in oblique relation to the rear face of the supporting plate 30 and resiliently engaging said plate and having a wedging action thereon whereby said device is clamped upon the supporting plate in said predetermined position.

17. In light reflecting means, a supporting member having an aperture therein, and a light reflecting device having a resilient securing part thereon extending transversely of the axis of the aperture and circumferentially of the light reflecting device and provided with a front edge 40 portion inclined relative to the rear face of the supporting member, said device and securing part being movable as a unit rearwardly within said aperture to a predetermined position during which movement the resilient securing part will 45 be forced inwardly by the supporting member, said resilient securing part springing outwardly when the reflecting device is moved to said position whereby the front edge portion of said resilient part will have a wedging action on the 50 supporting member serving to clamp the light reflecting device thereon.

18. In light reflecting means, a supporting member having an aperture therein, a light reflecting device having a resilient securing part 55 provided with a front edge portion inclined relative to the axis of the aperture and also having a cam-like portion, said device and resilient securing part being movable as a unit within said aperture to a predetermined position during which movement said cam-like portion will be engaged by the supporting member to force the securing part within the aperture, said resilient part upon movement of the light reflecting device to said predetermined position springing outwardly at 60 which time said edge portion will have a wedging action on the supporting member whereby to clamp the reflecting device upon the supporting member.

19. A light reflecting unit for insertion within 70 an aperture of a supporting plate including a lens, holding means for the unit mounted thereon rearwardly of the front end of the unit and including resilient parts extending laterally from the unit and provided with front and rear free edge portions, said unit and holding means when

assembled being movable from the front side of said supporting plate into and axially of said aperture at the completion of which movement the front edge portions of said resilient parts will be inclined relative to the plane of said supporting plate and have a wedging action on said plate. 5

20. A holder for a light reflecting unit adapted for application to the unit and for movement therewith into an aperture formed in a supporting member for the unit, said holder including a resilient part having a front edge portion inclined relative to the plane of the supporting member, said part being adapted for displacement inwardly by the supporting member during movement of the reflecting unit within the aperture to a predetermined position and automatically moving outwardly when the reflecting unit is at said position whereby said front edge portion will have a wedging action on the supporting member to secure the reflecting unit against movement in one direction within the aperture. 10 15 20

21. A holder for a light reflecting unit, said holder being adapted for application to the unit and for movement to a predetermined position 25 within an aperture formed in a supporting plate for the unit, said holder having thereon for movement therewith a resilient securing part provided with a front edge portion adapted when the unit is at said predetermined position to 30 extend interiorly and exteriorly of the aperture in oblique relation to the rear face of the supporting plate and to resiliently engage said plate and to have a wedging action thereon whereby to hold the light reflecting unit against axial 35 movement in an outward direction within the aperture.

22. A holder for a light reflecting device, said holder comprising a sleeve-like member adapted to be inserted upon said device and having a 40 resilient circumferentially extending securing part provided with a front edge portion inclined relative to the axis of the sleeve-like member, said light reflecting device and holder being movable as a unit to a predetermined position within 45 an aperture of a supporting member for said device during which movement the resilient securing part will be forced inwardly by the supporting member, said part springing outwardly when said device is moved to said predetermined position whereby the front edge portion of the resilient part will have a wedging action on the supporting member to secure the light reflecting device against axial movement in one direction within the aperture. 50 55

23. A holder for a light reflecting unit having a lens, said holder adapted for application to said light reflecting unit and having a resilient securing part provided with a front edge portion inclined relative to the axis of the unit and also 60 having a cam-like portion, said device and the holder being adapted for movement to a predetermined position within an aperture of a supporting member for the light reflecting unit during which movement said cam-like portion 65 will be engaged by the supporting member to force the securing part within the aperture, said resilient part upon movement of the light reflecting unit to said predetermined position springing outwardly at which time said edge portion 70 will have a wedging action on the supporting member whereby to hold the unit against axial movement in one direction within the aperture.
